LATERAL MOTION RESISTING DEVICE

James G. Blunt, Schenectady, N. Y.

Application April 29, 1931. Serial No. 533,699

16 Claims. (Cl. 105—80)

This invention relates to lateral motion resisting devices for railway vehicles.

An object of the invention is to provide a device applicable to one or more pairs of journal boxes of railway vehicles, which will provide resilient lateral movement of the wheels and journal boxes relative to the vehicle frame, thus equalizing rail flange pressures with adjacent wheels, assisting in passing track curves and absorb the lateral inertia thrusts against the vehicle frame, as well as the centrifugal forces set up while passing through curves or irregular track.

A further object is to provide an improved device wherein one journal box is designed to act as a thrust block, whereby the opposite box is returned to its normal position, and whereby lateral shocks that would otherwise be imparted to the vehicle frame by said opposite box are absorbed.

A further object is to provide a device of the character described wherein there is no pressure exerted by the device upon the boxes when they are in their normal positions.

A further object is to provide a flexible connection between each box and the adjacent end of the device, whereby the device is free to tilt in a vertical plane and the boxes are thus left free for vertical relative movement, the device thus maintaining parallelism with the axle for all positions of the boxes.

A further object is to provide a device of the character described which may be applied or removed without disturbing the boxes.

A further object is to provide a device which is held in position and supported by the boxes independent of the vehicle frame, thereby obviating the employment of frictional surfaces requiring lubrication.

A further object of the invention is to provide a device characterized by simplicity, low cost, and economical maintenance.

Further objects and advantages which are achieved by the instant invention will be apparent by the detailed description of a preferred embodiment of the invention hereinafter set forth.

While the invention is of broad application, its important field of usefulness, as at present believed, is in connection with the drive wheels of a locomotive. Therefore, while in no way so limiting it, the invention will be hereinafter described in connection with a locomotive. It will be also understood that in usual practice a lateral motion resisting device arrangement such as

hereinafter described, may be applied to one or more of the axles of a locomotive.

In the accompanying drawing showing a preferred embodiment of the invention:

Figure 1 is a front view of a pair of drive wheels and boxes, the pedestal shoes being removed, showing the invention applied thereto, with the left half of the lateral motion resisting device in section on the line I—I of Fig. 2; Fig. 2, at the right side is a section on the line II—II' 65 of Fig. 1, and at the left side is a section on the line II'—II' of Fig. 1, with various parts removed; and Fig. 3 is a partial plan view of Fig. 1, with various parts added and showing one of the lateral motion resisting devices in section on the 70 line III—III of Fig. 2.

The invention is herein exemplified in connection with the frame of a locomotive of the standard "bar" type, comprising two side members 1, 1, having pedestal jaws 1a, 1a, which are disposed at the maximum distance apart permissible under the limitation imposed by the width between the driving wheel hubs. In each of the pedestal jaws 1a, a driving box 2 is fitted between shoes and wedges 3, in the usual manner. The 75 driving boxes are of the usual construction and provide sufficient space, between their flanges 4 and the shoes and wedges 3, to permit lateral motion of the boxes relative to the pedestal jaws. An axle 5, having a pair of driving wheels 6, is 80 journalled in the driving boxes. Normally, as when the vehicle is passing over tangent track, the inner faces of the hubs of the wheels 6 are 85 next to the outer faces of their respective journal boxes and the inner flanges 4 of the boxes bear against the adjacent faces of their respective shoes and wedges, the space or clearance provided to permit lateral movement of the boxes 90 relative to the pedestal jaws being between the outer flanges 4 and the respective adjacent faces 95 of the shoes and wedges.

As the axle 5, is free to move laterally relative to the boxes, it will be apparent that the boxes are permitted independent lateral movement relative to each other, as well as to their respective pedestal jaws. From their afore-described normal positions, however, it will be seen that the boxes may move inwardly only, relative to their respective pedestal jaws, and 105 when one box is moved laterally inwardly, the opposite box, bearing against its pedestal jaw, acts as a thrust block for the resistance means, or lateral motion resisting devices of the present invention, as hereinafter fully described. On the 110

inner sides of the driving boxes, one on each side of the axle 5, are U-shaped supports 7.

Two lateral motion resisting devices are disposed one on each side of the axle, and each element comprises a pair of guide yokes 8, having holes 9 formed therein, through which holes are passed bolts 10. The bolts 10 are threaded at one of their ends and are provided with nuts 11. The nuts 11 are formed with sleeves which slidably fit within the adjacent holes 9. The guide yokes 8 are each formed with an integral inwardly extending stem 12, which is circular in cross-section, and an integral outwardly extending arm 13, which is oblong in cross-section, constituting in effect a thrust element. The outer ends of the arms 13 fit within the U-shaped supports 7, and the supports are provided with orifices 14, through which pins 15 are passed, the lateral motion resisting devices being thus held in a vertical position and being prevented from turning. Helical springs 16 are disposed around the stems 12, and a center spaces 17, comprising a plate 18, is fitted between the inner ends of the springs, and oppositely extending bosses 19 are formed on said plate, and extend within the adjacent ends of the springs. It will be understood that a single spring may be employed between the guide yokes, thus eliminating the spacer without departing from the spirit of the invention, the construction illustrated having the advantage however, or more elasticity and durability. A suitably shaped liner 20 may be inserted in one of the supports 7, at the end of the arm held thereby.

In operation, when a locomotive is passing through curved or irregular track the respective pairs of wheels and their axles are laterally moved relative to the vehicle frame, and the hub of the wheel of each pair, which is moved inwardly relative to the frame, being forced against the side of its adjacent box, and the box being thereby moved inwardly, the thrusts from the lateral movement are transmitted from this box to the frame. With the devices of the instant invention applied to oppositely disposed boxes, the shocks are transmitted from the inwardly moved box to its adjacent guide yoke 8, which being operably engaged with the springs 16 and slidably upon the bolts 10, transmit the thrusts to the springs 16, and as the devices bear against the opposite box, which in turn bears against the vehicle frame, a compression of the springs is effected as the said yokes are forced nearer together and the shocks are thus absorbed by said springs. The resiliency of the springs will tend to force the guide yokes outwardly and will assist in returning the wheels and the moving box to their normal lateral positions, when the vehicle returns to tangent track. While as aforesaid, the resisting devices are prevented from turning by the U-shaped supports, their flexible connections with their adjacent boxes permits the devices to tilt freely in a vertical plane and the boxes are thus unrestricted by the devices in their relative vertical movements, and the devices are maintained in parallelism with their adjacent respective axles for all positions of the boxes.

It will be apparent that the instant invention is especially adapted for application to locomotives in use, in that all that is necessary to be done to the locomotive, is to apply suitable supports to the boxes. The devices are then simply applied as units and their disposition and construction is such that they do not come in the

way of the crossties or frame structure of the locomotive. The removal of the pins 15, and liners 20, permits the devices to be removed as units.

The initial lateral resistance may be increased or decreased by adjusting the nuts 11, inserting the liner 20 to take up any excess lateral space caused by the drawing up of the springs to increase the resistance. The lateral motion resisting devices being suspended entirely upon the two boxes of the same axle will at all times be in alignment with the driving axle and the instant construction is such that there are no frictional surfaces which would require lubrication. Where it is desired to permit only a very limited lateral motion, solely for the purpose of softening blows against the frames the instant device is especially advantageous by reason of its simplicity, low cost, and ease of assemblage.

It will further be seen that in the operation of the instant device one box acts as a thrust bearing to take the thrust of the device produced by the opposite box. Of especial advantage is the fact that when the driving boxes are in their normal positions there is no pressure exerted upon the boxes whatever by the devices.

While there has been hereinbefore described an approved embodiment of the invention it will be understood that many and various changes and modifications may be made thereto without departing from the spirit of the invention, and that all and any such changes and modifications that fall within the scope of the appended claims are contemplated as a part of the instant invention.

The invention claimed and desired to be secured by Letters Patent, is:

1. In a railway vehicle, the combination of a main frame; a pair of journal boxes, each having the capacity of lateral movement relative to the frame from a normal position substantially in an inward direction only; and means disposed between and carried by said boxes for resisting lateral thrust of said boxes, one of said boxes serving as a thrust block for said means, while said means resists the thrust of said other box during the relative lateral movement of said other box.

2. In a railway vehicle, the combination of a main frame; a pair of journal boxes, each having the capacity of lateral movement relative to the frame from a normal position substantially in an inward direction only; and resilient means disposed between and carried by said boxes for resisting lateral thrust of said boxes, one of said boxes serving as a thrust block for said means, while said means resists the thrust of said other box during the relative lateral movement of said other box.

3. In a railway vehicle, the combination of a main frame; a pair of journal boxes, each having the capacity of lateral movement relative to the frame from a normal position substantially in an inward direction only; and means disposed between and carried by said boxes for resisting lateral thrust of said boxes, one of said boxes serving as a thrust block for said means, while said means resists the thrust of said other box during the relative lateral movement of said other box, said means being adapted to urge said thrust-exerting box to normal position when the thrust subsides.

4. In a railway vehicle, the combination of a pair of journal boxes having the capacity of lateral movement; and means disposed between said boxes and carried thereby for exerting lateral

- force upon one of said boxes while utilizing the other box as an abutment, to resist lateral movement of said first box and return the first box to normal position, when said first box is moved laterally away from said normal position. 5
5. A lateral motion resisting device comprising a plurality of helical springs; guide yokes engaging said helical springs at their respective outer ends and holding the springs in aligned positions; 10 a spacer disposed between the inner ends of said helical springs; means holding said guide yokes in operative position; and bearing members formed on said guide yokes extending outwardly therefrom. 15
6. In a railway vehicle, the combination of a pair of journal boxes having the capacity of lateral movement; supporting elements mounted on the inner sides of said journal boxes; and resilient means carried by said supporting elements 20 comprising a pair of aligned springs, a pair of guide yokes engaging the respective outer ends of said springs, and having extensions engaged with said supporting elements, and means holding said guide yokes in adjusted positions, whereby lateral force will be exerted against one of said boxes while the other of said boxes is utilized as an abutment, to resist lateral movement of said first box and to return said first box to normal position, when said first box is moved laterally 25 away from said normal position. 30
7. In a railway vehicle, the combination of a pair of journal boxes having the capacity of lateral movement; oppositely disposed U-shaped supports mounted on the inner faces of said boxes; resilient means disposed between said boxes in line with said oppositely disposed supports; guide yokes engaging the outer ends of said resilient means and engaging adjacent supports; and a liner adapted to be disposed in one 35 of said supports at the end of the adjacent yoke. 40
8. In a railway vehicle, the combination of a pair of journal boxes having the capacity of lateral movement; oppositely disposed U-shaped supports mounted on the inner faces of said boxes; resilient means disposed between said boxes in line with said oppositely disposed supports; guide yokes engaging the outer ends of said resilient means and engaging adjacent supports; and means for locking said guide yokes in 45 engagement with said supports. 50
9. In a railway vehicle, an axle having inside journals; a pair of wheels secured on the axle; journal boxes, having independent lateral movement relative to each other, for the journals; side frame members having pedestals engaging the boxes permitting independent, limited, lateral movement of the boxes; and a device disposed between and carried entirely by the boxes for yieldingly resisting inward movement of either 55 of the boxes relative to its engaging pedestal. 60
10. In a railway vehicle, an axle having inside journals; a pair of wheels secured on the axle; journal boxes having independent lateral movement relative to each other, for the journals; side frame members having pedestals engaging the boxes permitting independent, limited, lateral movement of the boxes; a device comprising yielding resistance means disposed between and carried entirely by the boxes for yieldingly resisting inward movement of either of the boxes relative to its engaging pedestal; and means for varying the degree of resistance of said resistance means. 70
11. In a railway vehicle, an axle having inside 75
- journals; a pair of wheels secured on the axle; journal boxes, having independent lateral movement relative to each other, for the journals; side frame members having pedestals engaging the boxes permitting relative vertical movement and independent, limited, lateral movement of the boxes; and a device disposed between and carried entirely by the boxes for yieldingly resisting inward movement of either of the boxes relative to its engaging pedestal, said device having a flexible connection with each of the boxes to permit the device to tilt as the boxes move vertically relative to each other. 80
12. In a railway vehicle, an axle having inside journals; a pair of wheels secured on the axle; journal boxes, having independent lateral movement relative to each other, for the journals; side frame members having pedestals engaging the boxes permitting independent, limited, lateral movement of the boxes; and a device disposed between and carried entirely by the boxes for yieldingly resisting inward movement of either of the boxes relative to its engaging pedestal, comprising separate end parts movable inwardly respectively with the inward movement of the adjacent box when moving relative to its engaging pedestal under lateral pressure of the adjacent wheel, and resilient means between the parts resisting said inward movement, said resilient means automatically returning said moved part by outward movement thereof to normal position when the pressure is released. 90
13. A railway vehicle comprising side frame members; oppositely disposed journal boxes engaging said frame members and having the capacity of lateral movement relative thereto; a helical spring disposed between the boxes; a support for the spring disposed between the ends thereof; and a rigid element at each end of the spring, with its outer end abutting against and carried by the inner wall of its adjacent box. 105
14. A railway vehicle comprising side frame members; oppositely disposed journal boxes engaging said frame members and having the capacity of lateral movement relative thereto; a pair of helical springs aligned between said boxes; guide yoke means holding said springs; and rigid elements at the opposite ends of said guide yoke means connected to and carried by the inner walls of the journal boxes. 110
15. A railway vehicle comprising side frame members; oppositely disposed journal boxes engaging said frame members and having the capacity of lateral movement relative thereto; a pair of helical springs aligned between said boxes; guide yoke means holding said springs and being adjustable to vary the amount of resistance offered by said springs; and rigid elements at the opposite ends of said guide yoke means connected to and carried by the inner walls of the journal boxes. 115
16. A railway vehicle comprising side frame members; oppositely disposed journal boxes engaging said frame members and having the capacity of lateral movement relative thereto; a helical spring disposed between the boxes; a support for the spring disposed between the ends thereof; a rigid element at each end of the spring, with its outer end abutting against the inner wall of its adjacent box; and supporting elements mounted on the inner faces of said boxes and engaging and carrying said rigid elements. 120
